UNITED STATES PATENT OFFICE.

WILLIAM L. TETER, OF PHILADELPHIA, PENNSYLVANIA.

MACHINE-BELTING.

SPECIFICATION forming part of Letters Patent No. 341,704, dated May 11, 1886.

Application filed October 6, 1885. Serial No. 179,125. (No model.)

To all whom it may concern:

Be it known that I, WILLIAM L. TETER, of the city and county of Philadelphia, and State of Pennsylvania, have invented an Improvement in Machine-Belts, of which the following is a specification.

My invention has reference to woven machine-belts; and it consists, essentially, of one or more layers of metal warp interposed between two or more layers of cotton warp, each layer being formed of two sets of warps and a suitable filling, and these layers of warps being bound together by suitable binding-warps, which extend entirely through the various layers and securely bind them together, and in details of construction, all of which are fully set forth in the following specification and shown in the accompanying drawings, which form part thereof.

20 I am aware that woven machine-belts have been made with metallic warp, and also metallic longitudinal strengthening-strands, and therefore do not here lay any claim to the generic use of metallic warp in belting of this 25 class; but the specific construction of belting as herein specified, as far as I am aware, is entirely new.

The object of this invention is to form a machine-belt which shall be non-extensible in 30 the direction of its length, and in which none of the layers of metallic warp should come in contact with the band-wheels, being thoroughly protected by layers of cotton warp, thereby producing not only a more perfect 35 belt, but one which shall have a greatly-increased durability.

In the drawings, Figure 1 is a longitudinal sectional elevation on line *x-x*, showing the various layers composing the belt and how 40 they are bound together; and Fig. 2 is a cross-section of same on line *y-y*.

It represents layers of cotton warp, and B represents layers of combined cotton and metal warp, in which E are the metal warps. 45 As is seen in Fig. 1, the layers embodying the metal warp are separated by the layers composed wholly of cotton warp, thereby being protected from each other, and as the outer layers are of cotton the metal warp is protected from being cut or worn by running over the pulleys or by coming in contact with external objects.

D are the filling-threads, and while in practice a single filling-thread is used, as indicated in dotted lines, passing between the warps of alternate layers, thus binding them thoroughly together at their edges, it is evident that each layer may have its own specific filling-thread.

The light dotted lines connecting the filling-threads indicate their passage at one edge of the belt, while the heavy dotted lines indicate their passage at the other edge of the belt, showing that a strong firm selvage is insured. These layers H and B are firmly bound together by the binding-warps F, which pass around the filling-threads of the two outer layers of the belt, thus binding every layer throughout their entire surface tightly together, making the belt extremely compact and entirely protecting the metallic portions thereof, and the peculiar construction prevents any possibility of the metallic warp working out while the belt is in use.

Any number of layers may be employed; but in all cases the outer layers are of cotton or fibrous material alone, while the alternate inner layers may be either metal alone or preferably metal and cotton combined; hence the belt may be three or more ply, as desired, and in some cases that face of the belt which runs next to the pulleys may have two layers of cotton in place of one, the second layer being indicated in dotted lines in Fig. 1.

Having now described my invention, what I claim as new, and desire to secure by Letters Patent, is—

1. In a woven machine-belt, three or more cotton layers of warps, every alternate layer being furnished with a series of metal warp, in combination with filling and binding threads to unite the several layers of warp to form a compact belt, substantially as and for the purpose specified.

2. In a woven machine-belt, three or more cotton layers of warps, every alternate layer being furnished with a series of metal warps, and in which the two outer layers are of cotton only, in combination with filling and binding threads to unite the several layers of warp to form a compact belt, substantially as and for the purpose specified.

3. A machine-belt composed of one or more layers of combined metallic and cotton warp

and three or more layers of cotton warp, the metallic warp being inclosed between the cotton layers of warp, and in which the wearing-surface, or that which runs next to the pulleys, 5 is made with a double layer of cotton warp, substantially as and for the purpose specified.

4. A machine-belt composed of one or more layers of combined metallic and cotton warp and three or more layers of cotton warp, the 10 metallic warp being inclosed between the cotton layers of warp, and in which the wearing-surface, or that which runs next to the pulleys, is made with a double layer of cotton warp, in combination with a single filling-thread, 15 which passes successively between the warp of each layer, substantially as and for the purpose specified.

5. A machine-belt consisting of the combi-

nation of the cotton warp H, the cotton and metallic warp B, interposed between them, 20 suitable filling-threads, and binding-warp, substantially as and for the purpose specified.

6. In a woven machine-belt, one or more layers of metallic warp interposed between two or more layers of cotton warp, in combination with suitable filling-threads and binding-warp, the latter passing entirely across 25 all the layers of warp, binding them together, substantially as and for the purpose specified.

In testimony of which invention I hereunto 30 set my hand.

WILLIAM L. TETER.
